UNITED STATES PATENT OFFICE.

HARVEY C. MUMMERT, OF BUFFALO, NEW YORK.

AIRPLANE.

1,274,745.

Specification of Letters Patent.

Patented Aug. 6, 1918.

Application filed January 18, 1918. Serial No. 212,514.

To all whom it may concern:

Be it known that I, HARVEY C. MUMMERT, a citizen of the United States, residing at Buffalo, in the county of Erie and State of New York, have invented certain new and useful Improvements in Airplanes, of which the following is a specification.

This invention relates to improvements in airplanes, and more particularly to control 10 mechanism for airplanes.

The object of my invention is to provide means whereby, by the manipulation of a lever, the impact-angle of the movable parts of both planes may be simultaneously and 15 equally changed, and thereby, by another lever acting through the same mechanism, said movable parts may be oppositely and equally changed. These and other objects will clearly appear from the following specifications and claims and from the drawings 20 in which,

Figure 1 is an outline plan view of an airplane provided with my improvements.

Fig. 2 is a detail plan view, partly in section, of my control mechanism.

Fig. 3 is a detail side elevation of the same.

The wings or planes 1 and 2 are rigidly secured to the body 3 in any well known 30 manner, and have the movable portions 4 and 5 at the rear of said planes. The movable portions 4 and 5 are rigidly secured to extensions of the shafts 6 and 7. These shafts 6 and 7 are supported in borings in 35 the bearing ends of the yoke 12 within bearings 8 and 9 secured to the follow boards of the body and passing through the sides of the body, as indicated at 10, and the extensions secured to the rigid portions of the 40 planes by hinge-clips, one of which is shown at 11 in Fig. 2.

A yoke casting 12, having bearing extensions 12^a which are within the bearings 8 and 9, has a handle at its forward end, and 45 at the base of which handle is a slot which takes over a segmental rack 13 which is secured to a fixed part of the machine. A rack-latch 14 within the handle portion of the yoke 12 is adapted to engage this rack 50 and to hold it in any desired position.

By releasing the latch 14 and moving the handle of the yoke 12, through the mechanism next described the movable portions 4 and 5 of the planes are given any desired 55 degree of inclination, thus producing the

same effect as increasing or decreasing the curvature of the entire wing portions.

Journaled in the yoke casting 12 is a shaft 15, and upon its outer end is a segmental bevel-gear 16. The two segments of this gear mesh, respectively, with the segmental bevel-gears 17 and 18, which are secured respectively to the inner ends of the shafts 6 and 7. Pivoted over the shaft 15 is a lever 19, which extends upwardly in front of the operator and projects downwardly below the shaft 15. This pivotal connection is such that said lever may be moved forward or back without movement of the shaft 15, while lateral movement of this lever in either 70 direction rotates the shaft 15. To this lever are secured cables 20 and 21 which control the elevators or horizontal rudders 22 and 23. This lever may thus be moved forward or back to control the said elevators without 75 movement of the shaft 15; but transverse movement of said lever rotates said shaft and moves said movable planes oppositely; and both movements of said lever effect movement of both elevators and plane members. 80

Thus movement of the yoke 12, through said gearing, changes the impact angle of the movable planes to increase or decrease the lifting power of both planes. Through 85 transverse movement of the lever 19, the impact angle of one of said planes is made greater and the other less to increase the lift of the one and to decrease that of the other for the purpose of correcting any lateral 90 tipping of the machine, or to control in banking and other movements; and by forward or back movement of said lever said elevators moved to control the forward and aft movement of the machine; and these 95 lever control operations may be employed separately or simultaneously. These means, therefore, afford the several controls stated, and both plane controls are effected through a single main mechanism which combines the 100 elements of simplicity, strength, and lightness which are essential in airplane construction.

Having thus described my invention, I claim:

1. In an airplane, the combination with pivoted side planes, and a rudder plane, of a yoke pivoted concentrically with the side planes, a rock-shaft carried by the yoke, gearing between the rock shaft and the side 110

planes, a lever pivoted to the rock shaft to swing in a plane parallel to the axis thereof, and connections between the lever and the rudder plane.

5. 2. In an airplane, the combination with pivoted side planes and a rudder plane, of a yoke pivoted concentrically with the side planes, a rock-shaft carried by the yoke

with its axis at a right angle to the axis of the yoke, a lever pivoted to the rock-shaft on an axis at a right angle to that of the shaft and adapted to rock said shaft, and connections between the lever and the rudder plane, to adjust the latter by movement of the lever on its own axis.

HARVEY C. MUMMERT.
